UNITED STATES PATENT OFFICE

157,466

RACK FOR TOWELS AND THE LIKE

Joseph Bornstein, Brookline, Mass., assignor to
Simplex Metal Products Co., Boston, Mass., a
corporation of Massachusetts

Application July 17, 1947, Serial No. 140,344

Term of patent 14 years

(Cl. D33—16)

To all whom it may concern:

Be it known that I, Joseph Bornstein, a citizen of the United States of America and a resident of Brookline, in the county of Norfolk, State of Massachusetts, have invented a new, original, and ornamental Design for a Rack for Towels and the like, of which the following is a specification, reference being had to the accompanying drawings, forming part thereof.

Figure 1 is a front elevation of a rack for towels and the like, embodying my new design.

Figure 2 is a top plan view of the rack shown in Figure 1.

Figure 3 is an end view of the rack.

A dominant and characterizing feature of my design consists in the arrangement of the horizontal bars thereof so that they are progressively and uniformly off-set from the topmost bar to the lowermost bar.

I claim:

The ornamental design for a rack for towels and the like, as shown and described.

JOSEPH BORNSTEIN.
